UNITED STATES PATENT OFFICE

131,158

DESIGN FOR A HORSE TRAINING CART

William Houghton Foster, Marion, Ohio, assignor to The Houghton Manufacturing Company,
Marion, Ohio, a corporation of Ohio

Application February 18, 1941, Serial No. 99,086

Term of patent 7 years

To all whom it may concern:

Be it known that I, William Houghton Foster, a citizen of the United States, residing at Marion, in the county of Marion and State of Ohio, have invented a new, original, and ornamental Design for a Horse Training Cart, of which the following is a specification, reference being had to the accompanying drawings, forming part thereof.

I claim:

The ornamental design for a horse training cart, as shown.

WILLIAM HOUGHTON FOSTER.
